United States Patent Office

Des. 198,615
Patented July 7, 1964

198,615

FAUCET FITTING

William H. Armstrong, Birmingham, Mich., assignor to Borg-Warner Corporation, Chicago, Ill., a corporation of Illinois

Filed July 30, 1963, Ser. No. 76,035

Term of patent 14 years

(CL. D91—3)

Fig. 1

Fig. 2

Fig. 4

FIG. 1 is a perspective view of the faucet fitting embodying my new design;

FIG. 2 is a top plan view thereof;

FIG. 3 is a side elevation view thereof; and

FIG. 4 is a front view thereof.

I claim:

The ornamental design for a faucet fitting, substantially as shown.
